BEATING ENGINE FOR PAPER PULP

Robert McNeill, Bury, England, assignor to McNeill
Winterburn Inventions Limited, Bury, England

Application June 15, 1951, Serial No. 231,805

12 Claims. (Cl. 92—22)

This invention is concerned with beating engines or "Hollanders" for the treatment of paper pulp.

Such machines comprise a large-diameter rotating roll mounted in bearings in a frame and having projecting blades or knives in its circumferential surface, the lower part of the roll co-operating with corresponding blades or knives in one or more bed-plates fixed in said frame, and the upper part of the roll being covered in by a hood or casing, between which and the top part of a portion of the frame known as the back-fall the bulk of the treated pulp is shot by centrifugal force.

One object of the invention is to increase the productivity rate of a beating engine by eliminating much of the idle time when the pulp is merely circulating in the trough. Another object is to increase productivity by introducing a milling effect so that, in addition to the grinding, crushing and cutting operations of the knives, there is also a pulverising operation, to a greater or less degree.

According to the invention, means is provided adjacent the top of the back-fall for periodically intercepting the usual flow of pulp over the back-fall and retaining the pulp in the roll chamber for a prolonged treatment. Means may be provided for automatically intercepting and resuming the flow of pulp at pre-determined intervals.

In the normal beating action, the pulp travels continuously around the Hollander, first under the roll, then over the back-fall and then round the trough back to the roll. In consequence, the pulp has to travel around the trough many times before it has been subjected to a sufficient beating action. In a Hollander according to this invention, as the pulp enters between the roll and the bed-plates, it is retained in the roll chamber for continuous beating action before being released for discharge over the back-fall.

The invention may be characterised by the provision of a wing valve between the top of the back-fall and the adjacent part of the roll cover (or an extension thereof), this valve, in one position closing the outlet over the back-fall, and in another position opening that passage. Such valve may be pivotally or hingedly mounted on the cover so as to hang pendulously from its pivot, being movable between a position where its lower edge engages or lies close to the back-fall to intercept the pulp, and a position where such lower edge is just clear of the roll, to direct the pulp over the back-fall. The usual doctor above the roll may be retained, but in such case will be lifted well off the roll, and in one arrangement the wing valve, when open, may co-operate with the doctor for guiding the pulp away from the roll. Alternatively, the doctor may be omitted.

The invention may include electric or electro-magnetic means or hydraulic or pneumatic means or mechanical means for the periodic opening and closing of the valve. When a hydraulic means is employed this may be under the control of a pressure and exhaust valve, and in one arrangement, this last-named valve is operated by a clock-controlled apparatus, whilst in another arrangement it is operated by a weight-controlled balance apparatus fed by running water. When a mechanical means is employed, this may be operated by means driven from the roll axle or from any part of the drive to the roll axle.

The invention may also be characterised by the fact that the valve is held in one extreme position by a spring or weight or the like, and is moved to the other extreme position (against the resistance of the spring or weight) by the operating mechanism, for example by a rotating

cam or by electro-magnetic means. In this last connection there may be an external arm on the pivot of the valve, to engage and be displaced by the operating means.

In its preferred forms therefore, the present invention 5 provides a pendulously-supported pivoted valve, above the back-fall of a beating engine, held in one position by a spring, and moved to the other position by a solenoid acting on a member outside the cover and fixed to the pivot of the valve, the valve in one of said positions closing 10 the outlet over the back-fall and compelling the pulp to remain in the beating chamber, and in the other of said positions opening that outlet and closing the space between the beater roll and the cover, to deflect the pulp over the back-fall.

15 Since in some circumstances it may not be desired to close the outlet over the back-fall, the invention may include means for holding the valve in the open position. This means, when the operation of the valve is by a solenoid, may be such as to hold the valve open without interfering in any way with the solenoid. For example, there 20 may be a pivoted latching member movable into and out of the path of the lever arm or the like on which the solenoid acts, and adapted when in that path to hold the lever arm against any return movement, with the valve 25 then in the open position.

According to this invention also, a beating engine is characterised by a hood or cover over the roll having on its inner face a series of deflectors, in the form of ridges, vanes, plates, corrugations or like obstacles, such that 30 any pulp which has not been thrown over the back-fall and is therefore carried around by the roll, when thrown against the cover by the roll is arrested by said deflectors or obstacles and falls back on to the knives, only to be again thrown off against the deflectors or obstacles further 35 around the roll, the repeated impact with the obstructions on the cover on the one hand and the rotating blades of knives on the other hand having a milling or reducing or pulverising effect on the pulp, which assists materially in bringing the "stuff" down to the required particle size 40 and condition.

A representative example of an arrangement according to the invention is illustrated in the accompanying drawing, wherein:

Fig. 1 is a diagrammatic vertical cross-section through 45 a beater roll and its associated parts, the valve being shown in the closed position in full lines and in the open position in broken lines;

Fig. 2 is an exterior elevation of the valve-operating means;

Fig. 3 is a sectional view (longitudinally of the roll) of 50 the valve-operating means, and

Fig. 4 is a side view showing the means for holding the valve open continuously when that is desired.

As shown, more particularly in Fig. 1, there is a trough 55 comprising the roll 1, the bedplate 2, the back-fall 3, and cover 4 over the roll, with an extension 5 over the back-fall. These parts may be of any normal construction, the back-fall being shown as built on a concrete foundation 6 of the trough.

mounted at 21, on a fixed part of the apparatus and is loaded by a spring plunger 22 so as to tend to move in a clock-wise direction (when seen as in Fig. 2). A rotary cam or eccentric 23 is mounted in bearing brackets 24 and is provided with a handle 25. The latch member 20 bears on the eccentric 23 and, in the position shown in Fig. 2, is held out of the path of the lever arm 12. The handle 25 rests on a stop member 26 extending from the bracket 17. However, when the handle 25 is rotated (clock-wise in Fig. 2) it allows the latch 20 to move in the same direction, bringing the lower end 20a into the path of the arm 12, whereupon, on the next upward movement of arm 12, the part 20a snaps into the notch 19 and holds the arm in the raised position.

The solenoid B may be energised intermittently by any suitable means, such as a time switch A, and this switch will, by preference, be adjustable. Clock mechanism may be employed to actuate a switch in the solenoid circuit, or there may be a rotary switch driven synchronously with the beater roll, or other control means may be employed.

Secured at intervals around the cover 4, on its outer face, are brackets 30 having upstanding portions 31 to the outer end of which is secured a boss 32. Passing through slots in the brackets 30 and through the cover 4 are deflector plates 33, the lower part of which projects through the cover into the space between the cover and the roll. As will be seen in the drawing, these plates 33, from the back-fall side of the roll onwards, are at progressively increasing angles to the vertical. The arrangement is such that, as pulp is thrown from the roll (more or less tangentially) at successive points around the roll, it meets the adjacent plate 33 at substantially the same angle.

To the top of each plate is secured a nut 34, in engagement with a screw 35 mounted in the boss 32, the screw being held against axial movement and being fitted with a handwheel 36. There will, of course be two or more brackets 30 for each plate, spaced along the cover in the direction of the roll axis.

In use, with the wing valve closed the pulp picked up by the roll is retained in the roll chamber and becomes subject to continuous action by the roll. However, when the solenoid is energised, the arm 12 is pulled up, which rotates the trunnions of the valve 7 and brings that valve to the open position where it also acts as a doctor or deflector to direct the pulp over the back-fall. When the solenoid is again de-energised, the spring 16 asserts itself to return the arm 12 and the valve 7 to the original positions. Any pulp not shot over the back-fall 3 becomes thrown off the roll and hits one of the plates 33, by which it is arrested and from which it falls back on to the roll 1. If thrown off the roll again, it hits another of the plates 33 and again falls on to the roll, eventually finding its way back to the trough ready to be taken up over the bedplates again by the roll.

Beating engines have been made in all sizes to suit the various paper mills, according to the requirements of their particular papers, and in many cases to suit the available floor space. Possibly, also, changes need to be made to suit the mill's power factor. This invention can be fitted to any size of beater and, under automatic timing control, raises the productive capacity of the beater by anything up to four times the normal.

Various classes of paper and various fibres, or mixtures of fibres, call for varying treatment in the beating process. This is easily met by roll adjustment in the usual way, and by setting of the timing of the valve so that the charge receives the required "wetting" or cutting," suitable for the particular papers being made.

When the beater is being filled with the raw fibre, the wing valve 7 is set at the open position, where it acts as a doctor, and the circulation of the beater charge is normal and the beating process can be carried out in the normal way. This also applies to colour mixing and the like.

I claim:

1. The method of treating pulp in a beating engine in which the pulp flows between a roll and a bedplate and finally over a backfall, said method comprising the steps of periodically intercepting the flow of pulp completely at the top of the backfall so as to cause all the pulp issuing from between the roll and the bedplate to pass over the roll repeatedly for prolonging treatment; and shooting the thus treated pulp over the backfall between the intervals of interception.

2. A beating engine for paper pulp comprising, in combination, a trough; a bedplate arranged in said

trough; a roll arranged in said trough above said bedplate; a backfall arranged in said trough adjacent to said roll; a continuous cover arranged above said roll and forming a continuous beating chamber extending from one end of said cover to the other and communicating at said other end directly with said trough, said one end of said cover and the top of said backfall being spaced from each other to define a passage for the pulp therebetween; a pulp interceptor arranged at the top of said backfall, said pulp interceptor having a length substantially equal to the width of said passage and being movable between an open position where it allows the pulp to be shot over said backfall, and a closed position where said interceptor completely stops the flow of pulp over said backfall; and means for periodically moving said interceptor between the open position and the closed position thereof so as to cause the pulp in said beating chamber to pass over said roll for continuous treatment between said roll and said bedplate.

3. A beating engine for paper pulp comprising, in combination, a trough; a bedplate arranged in said trough; a roll arranged in said trough above said bedplate; a backfall arranged in said trough adjacent to said roll; a continuous cover arranged above said roll and forming a continuous beating chamber extending from one end of said cover to the other and communicating at said other end directly with said trough, said one end of said cover and the top of said backfall being spaced from each other to define a passage for the pulp therebetween; a wing valve arranged at the top of said backfall, said wing valve having a length substantially equal to the width of said passage and being pivotable between an open position where it allows the pulp to be shot over said backfall, and a closed position where said wing valve completely stops the flow of pulp over said backfall; and means for periodically moving said wing valve between the open position and the closed position thereof so as to cause the pulp in said beating chamber to pass over said roll for continuous treatment between said roll and said bedplate.

4. A beating engine for paper pulp comprising, in combination, a trough; a bedplate arranged in said trough; a roll arranged in said trough above said bedplate; a backfall arranged in said trough adjacent to said roll; a continuous cover arranged above said roll and forming a continuous beating chamber extending from one end of said cover to the other and communicating at said other end directly with said trough, said one end of said cover and the top of said backfall being spaced from each other to define a passage for the pulp therebetween; a pivotally mounted wing valve arranged at the top of said backfall so as to hang pendulously from the pivot thereof, said wing valve having a length substantially equal to the width of said passage and being pivotable between an open position where the lower edge of said wing valve is just clear of said roll so as to allow the pulp to be shot over said backfall, and a closed position where said lower edge of said wing valve is close to said backfall so as to intercept the flow of pulp over said backfall; and means for automatically periodically moving said wing valve between the open position and the closed position thereof so as to cause the pulp in said beating chamber to pass over said roll for continuous treatment between said roll and said bedplate.

5. A beating engine for paper pulp comprising, in combination, a trough; a bedplate arranged in said trough; a roll arranged in said trough above said bedplate; a backfall arranged in said trough adjacent to said roll; a continuous cover arranged above said roll and forming a continuous beating chamber extending from one end of said cover to the other and communicating at said other end directly with said trough, said one end of said cover and the top of said backfall being spaced from each other to define a passage for the pulp therebetween; a wing valve arranged at the top of said backfall, said wing valve having a length substantially equal to the width of said passage and being pivotable between an open position where it allows the pulp to be shot over said backfall, and a closed position where said wing valve completely stops the flow of pulp over said backfall; means for holding said wing valve in one of said positions; and means for automatically periodically moving said wing valve between

the open position and the closed position thereof so as to cause the pulp in said beating chamber to pass over said roll for continuous treatment between said roll and said bedplate.

6. A beating engine for paper pulp comprising, in combination, an endless trough; a bedplate arranged in said trough; a roll arranged in said trough above said bedplate; a backfall arranged in said trough adjacent to said roll; a continuous cover arranged above said roll and forming a continuous beating chamber extending from one end of said cover to the other and communicating at said other end directly with said trough, said one end of said cover and the top of said backfall being spaced from each other to define a passage for the pulp therebetween; a wing valve arranged at the top of said backfall, said wing valve having a length substantially equal to the width of said passage and being pivotable between an open position where it allows the pulp to be shot over said backfall to pass around said trough, and a closed position where said wing valve completely stops the flow of pulp over said backfall; a spring for holding said wing valve in one of said positions; and means for automatically periodically moving said wing valve between the open position and the closed position thereof so as to cause the pulp in said beating chamber to pass over said roll for continuous treatment between said roll and said bedplate, said means for automatically periodically moving said interceptor including a solenoid arranged outside said cover and a movable member controlled by said solenoid and rigidly secured to the pivot of said wing valve.

7. A beating engine for paper pulp comprising, in combination, an endless trough; a bedplate arranged in said trough; a roll arranged in said trough above said bedplate; a backfall arranged in said trough adjacent to said roll; a continuous cover arranged above said roll and forming a continuous beating chamber extending from one end of said cover to the other and communicating at said other end directly with said trough, said one end of said cover and the top of said backfall being spaced from each other to define a passage for the pulp therebetween; a wing valve arranged at the top of said backfall, said wing valve having a length substantially equal to the width of said passage and being pivotable between an open position where it allows the pulp to be shot over said backfall to pass around said trough, and a closed position where said wing valve completely stops the flow of pulp over said backfall; a spring for holding said wing valve in one of said positions; and means for automatically periodically moving said wing valve between the open position and the closed position thereof so as to cause the pulp in said beating chamber to pass over said roll for continuous treatment between said roll and said bedplate, said means for automatically periodically moving said interceptor including a solenoid arranged outside said cover, a movable member controlled by said solenoid and rigidly secured to the pivot of said wing valve, and time switch means for automatically periodically actuating said solenoid.

8. A beating engine for paper pulp comprising, in combination, an endless trough; a bedplate arranged in said trough; a roll arranged in said trough above said bedplate; a backfall arranged in said trough adjacent to said roll; a continuous cover arranged above said roll and forming a continuous beating chamber extending from one end of said cover to the other and communicating at said other end directly with said trough, said one end of said cover and the top of said backfall being spaced from each other to define a passage for the pulp therebetween; a wing valve arranged at the top of said backfall, said wing valve having a length substantially equal to the width of said passage and being pivotable between an open position where it allows the pulp to be shot over said backfall to pass around said trough, and a closed position where said wing valve completely stops the flow of pulp over said backfall; a spring for holding said wing valve in one of said positions; means for automatically periodically moving said wing valve between the open position and the closed position thereof so as to cause the pulp in said beating chamber to pass over said roll for continuous treatment between said roll and said bedplate, said means for automatically periodically moving said

interceptor including a solenoid arranged outside said cover and a movable member controlled by said solenoid and rigidly secured to the pivot of said wing valve; and means for holding said wing valve continuously in the open position thereof when so desired.

9. A beating engine for paper pulp comprising, in combination, an endless trough; a bedplate arranged in said trough; a roll arranged in said trough above said bedplate; a backfall arranged in said trough adjacent to said roll; a continuous cover arranged above said roll and forming a continuous beating chamber extending from one end of said cover to the other and communicating at said other end directly with said trough, said one end of said cover and the top of said backfall being spaced from each other to define a passage for the pulp therebetween; a wing valve arranged at the top of said backfall, said wing valve having a length substantially equal to the width of said passage and being pivotable between an open position where it allows the pulp to be shot over said backfall to pass around said trough, and a closed position where said wing valve completely stops the flow of pulp over said backfall; a spring for holding said wing valve in one of said positions; means for automatically periodically moving said wing valve between the open position and the closed position thereof so as to cause the pulp in said beating chamber to pass over said roll for continuous treatment between said roll and said bedplate, said means for automatically periodically moving said interceptor including a solenoid arranged outside said cover, time switch means for automatically periodically actuating said solenoid, and a movable member controlled by said solenoid and rigidly secured to the pivot of said wing valve; and a pivoted latching lever movable into and out of the path of said member controlled by said solenoid so as to hold said member against any return movement when said wing valve is in the open position thereof.

10. A beating engine for paper pulp comprising, in combination, an endless trough; a bedplate arranged in said trough; a roll arranged in said trough above said bedplate; a backfall arranged in said trough adjacent to said roll; a continuous cover arranged above said roll and forming a continuous beating chamber extending from one end of said cover to the other and communicating at said other end directly with said trough, said one end of said cover and the top of said backfall being spaced from each other to define a passage for the pulp therebetween; a pulp interceptor arranged at the top of said backfall, said pulp interceptor having a length substantially equal to the width of said passage and being pivotable between an open position where it allows the pulp to be shot over said backfall to pass around said trough, and a closed position where said interceptor completely stops the flow of pulp over said backfall; means for automatically periodically moving said interceptor between the open position and the closed position thereof so as to cause the pulp in said beating chamber to pass over said roll for continuous treatment between said roll and said bedplate; and a plurality of deflectors arranged on the inner face of said cover, said deflectors arresting any pulp bypassing said backfall and carried around by said roll so as to fall back on said roll and to be carried along by the same into the space between said bedplate and said roll.

11. A beating engine for paper pulp comprising, in combination, an endless trough; a bedplate arranged in said trough; a roll arranged in said trough above said bedplate; a backfall arranged in said trough adjacent to said roll; a continuous cover arranged above said roll and forming a continuous beating chamber extending from one end of said cover to the other and communicating at said other end directly with said trough, said one end of said cover and the top of said backfall being spaced from each other to define a passage for the pulp therebetween; a pulp interceptor arranged at the top of said backfall, said pulp interceptor having a length substantially equal to the width of said passage and being pivotable between an open position where it allows the pulp to be shot over said backfall to pass around said trough, and a closed position where said interceptor completely stops the flow of pulp over said backfall; means for automatically periodically moving said interceptor between the open position and the

closed position thereof so as to cause the pulp in said beating chamber to pass over said roll for continuous treatment between said roll and said bedplate; and a plurality of plates arranged at progressively increasing angles to the vertical arranged on the inner face of said cover, said plates arresting any pulp bypassing said backfall and carried around by said roll so that the same meets said plates at substantially the same angle so as to fall back on said roll and to be carried along by the same into the space between said bedplate and said roll.

12. A beating engine for paper pulp comprising, in combination, an endless trough; a bedplate arranged in said trough; a roll arranged in said trough above said bedplate; a backfall arranged in said trough adjacent to said roll; a continuous cover arranged above said roll and forming a continuous beating chamber extending from one end of said cover to the other and communicating at said other end directly with said trough, said one end of said cover and the top of said backfall being spaced from each other to define a passage for the pulp therebetween; a pulp interceptor arranged at the top of said backfall, said pulp interceptor having a length substantially equal to the width of said passage and being pivotable between an open position where it allows the pulp to be shot over said backfall to pass around said trough, and a closed position where said interceptor completely stops the flow of pulp over said backfall; means for automatically periodically moving said interceptor between the open position and the closed
